UNITED STATES PATENT OFFICE.

FRED E. WHIPPLE AND HARRY W. WHIPPLE, OF WESTERLY, RHODE ISLAND.

DESIGN FOR A PLATE FOR WASHING-MACHINES.

SPECIFICATION forming part of Design No. 27,102, dated May 25, 1897.

Application filed April 8, 1897. Serial No. 631,324. Term of patent 7 years.

To all whom it may concern:

Be it known that we, FRED E. WHIPPLE and HARRY W. WHIPPLE, of Westerly, in the county of Washington and State of Rhode Island, have invented and produced a new and original Design for a Plate for Attachment to Washing-Machines, of which the following is a full, clear, and exact description.

Reference is to be had to the accompanying drawings, forming a part of this specification, in which similar characters of reference indicate corresponding parts in both the figures.

Figure 1 is a plan view of a plate for attachment to washing-machines embodying our new design, and Fig. 2 is a cross-sectional view on the line 2 2 of Fig. 1.

The design comprises a substantially plane shield-like plate whose edges are scalloped, the central scallops projecting beyond those

at the ends. The top edge shows a depressed center and inwardly and downwardly inclined convexities at each side of the center, while the lower edge is rounded.

A leading feature of our design resides in the scalloped plate having the upper edge presenting inwardly and downwardly inclined lines. Another leading feature is the central scallops projecting beyond the others, and the rounded lower edge.

We claim—

The design for a plate for attachment to washing-machines herein shown and described.

FRED E. WHIPPLE.
HARRY W. WHIPPLE.
